CIRCUIT BREAKER

John G. Jackson, Detroit, Mich., assignor to
 Square D Company, Detroit, Mich., a corpora-
 tion of Michigan

Application December 22, 1951, Serial No. 262,918

14 Claims. (Cl. 200—116)

1

This invention relates to apparatus for making and breaking electrical circuits and more particularly to circuit breakers automatically operable in response to current overloads and manually operable with a snap action.

An object of the present invention is to provide an improved form of quick make and quick break automatic electric circuit breaker of simple and economical construction.

A further object of the present invention is to provide an improved form of snap-acting mechanism requiring a reduced handle movement and, therefore, reduced operating space to effect the desired snap action.

A further object of the present invention is to provide an improved form of circuit breaker mechanism in which the operating mechanism is pivoted in the side walls of the casing and side cover.

Further objects and features of the invention will be readily apparent to those skilled in the art from the following specifications and appended drawings illustrating certain embodiments of the invention in which:

Figure 1 is a side view of the circuit breaker with the side cover removed and showing the operating mechanism in the "on" position, certain parts being broken away to facilitate the showing of other parts.

Figure 2 is a horizontal sectional view of the circuit breaker taken along the lines II—II of Figure 1.

Figure 3 is an enlarged horizontal sectional view taken along the lines III—III of Figure 2.

Figure 4 is a view similar to Figure 1, with the parts illustrated in the "off" position.

Figure 5 is a view similar to Figure 1, the parts being shown in the "tripped" position.

The circuit breaker as shown comprises an open sided casing 1 of molded insulating material in which the breaker contacts and operating mechanism are mounted. A cover 2 of insulated material providing additional mounting surfaces closes the open side of the casing 1 and is mounted thereon by means of a plurality of rivets 3. The casing and cover have integral vertical barriers 4 and 5 which form chambers within the interior of the circuit breaker. A conducting strap 6 is provided at one end ledge 7 of the casing 1, and fits into cutout slots 8 in the casing 1 and side cover 2 which hold strap 6 in place. A threaded terminal screw 9 fits into a threaded hole cut within the conducting strap and provides means for external connection of the breaker into an electrical circuit. Conducting

2

strap 6 extends through the casing and carries at its inner extremity a stationary contact 11 which is isolated from the adjacent casing and cover by means of an insulating material 12 which forms an arc chamber surrounding the stationary contact. A switching member 13 carrying a movable contact 14 on one end and having a latching surface 15 at the opposite end is provided, and has formed therein a notch 17 which is pivotally mounted on the bight of a generally U-shaped member 16. The legs of U-shaped member 16 have outwardly turned extensions 19 which are pivotally mounted in cutout portions 18 in the side casing 1 and cover 2.

An end ledge 21 is formed by the end of the casing opposite to the end which forms ledge 7. Upon ledge 21 there is mounted a second conducting strap 22 which is secured in cutout notches 23 in the casing 1 and cover 2. The conducting strap 22 extends into the interior of the device, and has a pressed out central portion 24 near its interior end to which is welded an end of a bimetallic member 25. An element 26 is carried in extensions of the cutout portions 23 adjacent the upper interior end of portion 24. Element 26 has a threaded hole therein in which a stud 27 operates, stud 27 engaging portion 24 to bent it and thereby change the position of the bimetallic member 25 to effect calibration of the breaker.

The current responsive tripping means of the circuit breaker, which is more fully described in my copending application for Circuit Breaker, Serial Number 776,528 filed September 27, 1947, now U. S. Patent No. 2,579,673, granted December 25, 1951, comprises a stationary magnetic yoke 28, a magnetic armature 29 and a resilient latching element 31 mounted upon the bimetallic member 25 and movable bodily therewith and relative thereto. The magnetic yoke 28 and the resilient latching element 31 are secured to the bimetallic member 25 as by means of a rivet 32, and the magnetic armature 29 is pivoted on an upper hook portion 33 of element 31 by means of a slot 34 in the armature 29. The latching element 31 is provided with a latching nose 30 as shown in Figure 4 and has a flange 35 at its back end which engages the bimetal 25. The yoke 28 is of generally U-shaped cross section as shown in Figure 2 so that the yoke 28 is energized magnetically by the current flow through the bimetallic member 25. A flexible conductor 36 interconnects the bimetallic member 25 and the switching member 13, each end of conductor 36 being welded to one of these members.

An operating handle 37 has a hub 38 which is pivotally mounted in suitable depressions in the side casing 1 and cover 2. Handle 37 has an internally extending arm 39 which is provided with a boss 41. A generally U-shaped operating member 42 having cutout portions at 43 and 44 has legs 46 which are pivoted in the side casing 1 and cover 2 in slots 45 provided therein, as shown in Figure 3. Member 42 also has a slot 52 therein through which member 13 extends in the "open circuit" position. The boss 41 is fitted into the cutout portion 43 to move the operating member 42 about its pivotal mounting upon movement of the operating handle 37. A return bent operating spring 47 has its ends secured to spaced, depending legs 48 of the operating member 42, and fits at its return bent portion in a slot 49 in the switching member 13.

Barrier 5 is provided with a surface at 53 which operates as a limit for movement of the switching member 13 when the circuit breaker is tripped.

The operation of the circuit breaker according to the present invention will now be explained. Referring to Figure 1 in which the circuit breaker is shown in the contacts engaged, or "on," position, the contacts may be manually disengaged by rotation of the handle 37 in the clockwise direction. Clockwise movement of the handle 37 produces counter-clockwise rotation of the operating member 42 about its pivotal engagement in slots 45 in the casing 1 and cover 2. This movement carries the extending legs 48 of the operating member 42 downwardly, until the ends of spring 47 attached thereto pass the point of the pivotal engagement between the U-shaped member 16 and cutout portions 18 of the casing 1 and cover 2. Spring 47 is then in a position in which its resiliency causes rotation of the U-shaped member 16, and the switching member 13 therewith, about its pivotal mounting in the casing 1 and cover 2, to separate rapidly the movable contact 14 from stationary contact 11. It should be noted that if the spring 47 should break or if the contacts should "freeze," the upper edge of slot 44 will engage the spring member 16 as operating member 42 pivots, and a positive force will be applied to rotate member 16 toward the open circuit position. Switching member 13 will thereby be moved to open circuit position.

In order to close the circuit through the circuit breaker after manual opening, handle 37 is rotated in a counter-clockwise direction. Operating member 42 thereby is rotated in a clockwise direction by virtue of the boss 41—slot 43 connection, and the ends of spring 47 connected to the legs of member 42 are moved upwardly. When these ends pass the point of the pivotal engagement of the member 16 in the cutout portions 18, the movable contact 14 is returned into engagement with the stationary contact 11 with a snap action.

Referring again to the position of the circuit breaker element as shown in Figure 1, should an overload occur in the circuit with which the circuit breaker is associated, either a sudden large surge which operates the magnetic armature member 29 against the latching nose 30 or a sustained smaller overload which flexes the bimetallic member 25 to carry the latching nose 30 to the position where it releases the latching surface 15 of the switching member 13, the latching surface 15 of the switching member 13 is then released and the switching member 13 is rotated

into the position shown in Figure 5 about its pivotal engagement in the bight of the U-shaped member 16 under the bias developed by the operating spring 47. Upon the occurrence of such an overload, the movable contact 14 is rapidly disengaged from the stationary contact 11 to effect a snap acting trip release of the circuit breaker. The latched end of the switching member 13, upon the occurrence of an overload in the circuit breaker, travels toward the top of the breaker until it engages ledge 53 of the barrier 5. Operating member 42 is rotated by spring 47 to the position of Figure 5, whereby handle 37 moves to an intermediate "tripped" position. To effect relatching of the circuit breaker mechanism, the operating handle 37 is rotated to its extreme clockwise position in which rotation the upper surface of slot 52 of the operating member 42 engages the switching member 13 forcing it downwardly until the latching surface 15 passes below the latching nose 30. The device is then again under manual control, the parts being in the position illustrated in Figure 4, which is also the position of the parts after the circuit breaker has been manually turned "off."

The circuit breaker mechanism of the present invention provides the features of quick-make and quick-break within a reduced arc of movement of the operating handle as is developed by the knee action operating mechanism. Furthermore, the device has a minimum number of parts, and is extremely rugged and durable. The device also provides for opening of the circuit therethrough despite a failure of the operating spring or a tending of the contacts to weld together.

While a certain preferred embodiment of the invention has been specifically disclosed, it is understood that the invention is not limited thereto, as many variations will be readily apparent to those skilled in the art and the invention is to be given its broadest possible interpretation within the terms of the following claims.

What is claimed is:

1. An automatic electric circuit breaker having a stationary contact, current responsive latching means, a switching member having a contact surface at one end cooperating with said stationary contact and a latching surface at its opposite end having a releasable engagement with said latching means, a U-shaped member pivoted on a fixed part and pivotally mounting said switching member, a manual operator, an operating member pivoted at one end on a fixed part and engaging said operator near its opposite end so as to be movable in response to movement of said manual operator, and spring means interconnecting said switching member and said operating member for moving said switching member to open and closed circuit positions in response to movement of said operator.

2. An automatic electric circuit breaker having a stationary contact, current responsive latching means, a switching member having a contact surface at one end cooperating with said stationary contact and a latching surface at its opposite end having a releasable engagement with said latching means, a U-shaped member pivoted on a fixed part and pivotally mounting said switching member, a manual operator, an operating member pivoted at one end on a fixed part and engaging said operator near its opposite end so as to be movable in response to movement of said manual operator, spring means interconnecting said switching member and said

operating member for moving said switching member to open and closed circuit positions in response to movement of said operator, and means on said operating member for applying a positive force to said U-shaped member when said manual operator is moved to the "off" position whereby movement of said switching member to the open circuit position is effected despite a failure of said spring means.

3. An automatic electric circuit breaker having a stationary contact, current responsive latching means, a switching member having a contact surface at one end cooperating with said stationary contact and a latching surface at its opposite end having a releasable engagement with said latching means, a U-shaped member pivoted on a fixed part and pivotally mounting said switching member, a manual operator having a pin thereon, an operating member pivoted on a fixed part and having a slot which cooperates with said pin whereby movement of said manual operator effects movement of said operating member about its pivot, and spring means interconnecting said switching member and said operating member for moving said switching member to open and closed circuit positions in response to movement of said operator.

4. An automatic electric circuit breaker having a stationary contact, current responsive latching means, a switching member having a contact surface at one end cooperating with said stationary contact and a latching surface at the opposite end having a releasable engagement with said latching means, a U-shaped member pivoted on a fixed part, said switching member having a pivotal engagement with the bight of said U-shaped member, a manual operator, an operating member pivoted at one end on a fixed part and engaging said operator near its opposite end, and spring means secured at one end to said operating members and at its other end to said switching member for moving said switching member to open and closed circuit positions in response to movement of said operator, said spring means biasing said U-shaped member into its pivot on said fixed part and biasing said switching member into its pivotal engagement with said U-shaped member.

5. An automatic electric circuit breaker having a cup-shaped casing and an insulating side cover cooperating therewith, a stationary contact and a current responsive latching means mounted within said side casing and cover, a switching member having a contact surface at one end cooperating with said stationary contact and a latching surface at the opposite end having a releasable engagement with said latching means, a U-shaped member pivoted on a fixed part and having a pivotal engagement with said switching member, a manual operator, an operating member pivoted at one end on a fixed part and engaging said operator near its opposite end, said casing and cover having lateral notches cut therein providing said fixed parts, and spring means interconnecting said switching member and said operating member and providing a bias for moving said switching member about its pivotal mounting on said U-shaped member and for moving said U-shaped member about its pivotal engagement on said fixed part.

6. An automatic electric circuit breaker having a cup-shaped casing and an insulating side cover cooperating therewith, a stationary contact and current responsive latching means mounted within said casing and cover, a switching mem-

ber having a contact surface at one end cooperating with said stationary contact and a latching surface at one end cooperating with said stationary contact and a latching surface at the opposite end having a releasable engagement with said latching means, a U-shaped member pivoted on a fixed part and having pivotal engagement with said switching member, a manual operator, an operating member pivoted at one end on a fixed part and engaging said operator near its opposite end, said side casing and cover having lateral notches cut therein providing said fixed parts, and spring means interconnecting said switching member and said operating member, said spring means biasing said contact surface against said stationary contact when they are engaged and biasing said switching member for rotation about its pivotal engagement with said U-shaped member when said latching surface is released by said current responsive latching means.

7. An automatic electric circuit breaker having a cup-shaped casing and an insulating side cover cooperating therewith, a stationary contact and current responsive latching means mounted in said casing, a switching member having a contact surface at one end cooperating with said stationary contact and a latching surface at the opposite end having a releasable engagement with said latching means, a U-shaped member pivoted by the legs thereof in said casing and cover and having a pivotal engagement with said switching member, a manual operator, an operating member, said operating member having a substantially U shape and having a pivoted engagement at one portion thereof with said side casing and cover and engaging said operator at another portion thereof so as to be movable therewith, and spring means interconnecting said switching member and said operating member for moving said switching member in response to movement of said manual operator.

8. An automatic electric circuit breaker having a cup-shaped casing and an insulating side cover cooperating therewith, a stationary contact and current responsive latching means mounted in said casing, a switching member having a contact surface at one end cooperating with said stationary contact and a latching surface at the opposite end having a releasable engagement with said latching means, a generally U-shaped member having one leg thereof pivoted in said casing and the other leg pivoted in said cover, said switching member having a return bent portion which is pivotally mounted upon the bight of said U-shaped member, a manual operator having a portion extending within said breaker which carries a pin, an operating member having a slot with which said pin cooperates whereby said operating member is moved by movement of said manual operator, means pivotally mounting said operating member in said casing and cover, and spring means interconnecting said switching and said operating member for moving said switching member in response to movement of said manual operator.

9. An automatic electric circuit breaker having a cup-shaped casing and an insulating side cover cooperating therewith, a stationary contact and current responsive latching means mounted in said casing, a switching member having a contact surface at one end cooperating with said stationary contact and a latching surface at the opposite end having a releasable engagement with said latching means, a generally

U-shaped member having one leg thereof pivoted in said casing and the other leg pivoted in said cover, said switching member having a return bent portion which is pivotally mounted upon the bight of said U-shaped member, a manual operator having a portion extending within said breaker which carries a pin, an operating member generally U-shaped in cross section, means pivotally mounting said operating member in said casing and cover, said operating member having a slot within which said pin operates whereby said operating member is moved upon movement of said manual operator, a pair of legs depending from said operating member, a U-shaped spring, the ends of said spring being mounted to said legs and the bight of said spring engaging said switching member at a point spaced from the pivotal connection of said switching member, rotation of said manual operator effecting movement of said ends of said spring across the point of mounting of said U-shaped member whereby said switching member is moved to open and closed circuit positions.

10. An automatic electric circuit breaker having a cup-shaped casing and an insulating side cover cooperating therewith, a stationary contact and current responsive latching means mounted in said casing, a switching member having a contact surface at one end cooperating with said stationary contact and a latching surface at the opposite end having a releasable engagement with said latching means, a generally U-shaped member having one leg thereof pivoted in said casing and the other leg pivoted in said cover, said switching member having a return bent portion which is pivotally mounted upon the bight of said U-shaped member, a manual operator having a portion extending within said breaker which carries a pin, an operating member generally U-shaped in cross section, means pivotally mounting said operating member in said casing and cover, said operating member having a slot within which said pin operates whereby said operating member is moved upon movement of said manual operator, a pair of legs depending from said operating member, a U-shaped spring, the ends of said spring being mounted to said legs and the bight of said spring engaging said switching member at a point spaced from the pivotal connection of said switching member, rotation of said manual operator effecting movement of said ends of said spring across the point of mounting of said U-shaped member whereby said switching member is moved to open and closed circuit positions, said switching member pivoting about its engagement with said U-shaped member under the bias of said spring when released by said latching means to move to an open circuit position.

11. An automatic electric circuit breaker having an insulating base, a manual operator, a stationary contact, a switching member carrying a contact surface at one end cooperating with said stationary contact, current responsive latching means for the opposite end of said switching member, a U-shaped member having its legs pivotally mounted in said base, said switching member having a return bent portion on an upper surface intermediate its ends pivotally engaging the bight of said U-shaped member, an operating member pivoted in said base and operatively connected to said manual operator whereby movement of said manual operator effects pivotal movement of said operating member, an operating spring having one por-

tion connected to said operating member and another portion connected to said switching member at a point on the lower surface thereof, movement of said manual operator effecting movement of the line of force of said spring across the point of pivotal mounting of said U-shaped member whereby said switching member is moved to open and closed circuit positions, said switching member pivoting about its engagement with said U-shaped member under the bias of said spring when released by said latching means to move to an open circuit position.

12. An automatic electric circuit breaker having a cup-shaped casing and an insulating side cover cooperating therewith, a stationary contact and current responsive latching means mounted in said casing, a switching member having a contact surface at one end cooperating with said stationary contact and a latching surface at the opposite end having a releasable engagement with said latching means, a generally U-shaped member having one leg thereof pivoted in said casing and the other leg pivoted in said cover, said switching member having a return bent portion which pivotally engages the bight of said U-shaped member, a manual operator having a portion extending within said breaker which carries a pin, an operating member generally U-shaped in cross section, means pivotally mounting said operating member in said casing and cover, said operating member having a slot within which said pin operates whereby said operating member is moved upon movement of said manual operator, a pair of legs depending from said operating member, a U-shaped spring, the ends of said spring being mounted to said legs and the bight of said spring engaging said switching member at a point spaced from the pivotal connection of said switching member, rotation of said manual operator effecting movement of said ends of said spring across the point of mounting of said U-shaped member whereby said switching member is moved to open and closed circuit positions, and means on said operating member for applying a positive force to said U-shaped member when said manual operator is moved to the "off" position whereby movement of said switching member to the open circuit position is effected despite a failure of said spring.

13. An automatic electric circuit breaker having a cup-shaped casing and an insulating side cover cooperating therewith, relatively movable contacts and means releasable for effecting relative movement of said contacts, current responsive means normally restraining said releasable means and effecting release upon the occurrence of overcurrent through the circuit breaker, a U-shaped member pivoted in said casing and cover at its legs and pivotally engaging at its bight said releasable means, a manual operator pivoted in said side casing and cover, an operating member pivoted at one end in said side casing and cover and engaging said operating member near its opposite end, a spring interconnecting said operating member and said releasable means, said spring biasing said contacts toward each other in engaged position and away from each other in disengaged position and biasing said releasable means for rotation about said U-shaped member upon release of said releasable means.

14. An automatic electric circuit breaker having an open sided casing and an insulating side cover cooperating therewith, relatively movable

contacts and means releasable for effecting relative movement of said contacts, current responsive means normally restraining said releasable means and effecting release on the occurrence of overcurrent, a U-shaped member pivoted in said side casing and cover at its legs and pivotally engaging at its bight said releasable means, a manual operator pivoted in said side casing and cover, an operating member pivoted at one end in said side casing and cover and engaging said operating member near its opposite end, a spring interconnecting said operating member and said releasable means, said spring biasing said contacts toward each other in engaged position and

away from each other in disengaged position and biasing said releasable means for rotation about said U-shaped member upon release of said releasable means, and means on said operating member for positively effecting movement of said releasable means to an open circuit position despite failure of said spring.

JOHN G. JACKSON.
